RUDOLPH HERMANN MC HARDY, OF LONDON, ENGLAND.

PNEUMATIC FOR KEYBOARD MUSICAL INSTRUMENTS.

No. 894,847.

Specification of Letters Patent.

Patented Aug. 4, 1908.

Application filed November 5, 1907. Serial No. 400,888.

To all whom it may concern:

Be it known that I, RUDOLPH HERMANN MC HARDY, a subject of the King of Great Britain and Ireland, residing at London, England, have invented a certain new and useful Improvement in Pneumatics for Keyboard Musical Instruments, of which the following is a specification.

This invention relates to pneumatics for use in mechanically-operated keyboard musical instrument such as automatic pianos.

The object of the invention is to effect certain improvements in the construction of such pneumatics to the ends that the parts therefor can be manufactured and assembled quickly and at small cost, that the completed pneumatics shall give reliable, uniform and efficient operation, and that the pneumatics for an instrument may be so compactly arranged as to occupy but small space.

In accordance with the invention, the pneumatics are built in pairs, each pair having a common, central wall and two movable walls one on either side of the common wall and connected thereto by the usual flexible covering, the two pneumatics being adapted to be collapsed and inflated independently and their movable walls being connected to independent keys of the instrument. The valves controlling the entrance and exit of air to and from the double pneumatic are located in the central wall. By this arrangement of the parts, the pneumatics for an instrument can be so compactly arranged as to occupy little space within the casing; thus, with this construction of pneumatic, automatic operating mechanism may be installed within an upright piano of the usual type without any change in the casing thereof.

The preferred embodiment of the invention is illustrated in the accompanying drawings, in which

Figure 1 is a section through one of the double pneumatics; Fig. 2 is a similar view broken away in part, illustrating one of the valves; Fig. 3 is a transverse section on line 3—3 of Fig. 1; Fig. 4 is a transverse section on line 4—4 of Fig. 2; and Fig. 5 is a detail view hereinafter referred to.

Referring to these drawings, the suction- or vacuum-chest of the instrument is shown at 1, this chest consisting of a long box of rectangular cross-section extending the length of the instrument and connected to the air-pump by which air is exhausted

therefrom. The pneumatics may be mounted upon this chest and are shown as so supported in the drawings. Each of the double pneumatics consists of a common central wall 2 and two movable walls 3 and 4 hinged to opposite sides of the central wall. Coverings 5 of flexible material, such as kid, are secured to the edges of the central and movable walls in the usual manner, these coverings being creased as shown in Fig. 3, so that they will fold readily when the pneumatics are collapsed. The movable walls 3 and 4 are connected by suitable rods with independent keys of the instrument, the wall 4 being shown as connected directly with a key by a rod 6 and the wall 3 by a rod 7 through a pivoted lever 8, this arrangement of the rods being adopted in order that the pneumatics may be disposed in a horizontal position.

In order to secure a compact arrangement of the parts, the valves controlling the entrance and exit of air to and from the pneumatics are arranged within the central wall 2 of the double pneumatic. For this purpose, wall 2 is formed in two parts as shown in the drawings, these parts being hinged together along one side, preferably by employing a piece of textile fabric 9 pasted to the adjacent edges of the two pieces. Within each of the two parts of the central wall 2 is a valve for controlling the passage of air to one of the pneumatics and a valve-operating means controlling the operation of the valve in the other part of the central wall.

As shown in Figs. 1, 2 and 3, the adjacent faces of the two parts of wall 2 are cut away through a portion of their length so as to form an opening 10 when the two parts are brought together, which opening is adapted for connection with the suction-chamber 1. The construction of each of the valves is best shown in Fig. 2, from which it will be seen that the part 11 of the central wall 2 has a circular opening 12 cut therein, communicating with the passage 10 and two openings 13 and 14 leading from the opening 12, one to the outer face of the part 11 (that is, to the interior of the pneumatic), and the other to the side of the part 11 (that is, to the atmosphere). Within the opening 12, is a valve 15, consisting of a disk of fiber having disks of thin leather secured to opposite faces thereof and a stem 16 projecting upwardly therefrom and loosely connected with the valve 15. A metallic annulus 17 is secured upon the part 11, partially closing the opening 12. The

inner edge of this annulus is provided with a narrow flange, as shown in Fig. 2, adapted for coaction with the valve 15. The stem 16 of the valve projects through the opening in the annulus 17 for coaction with the valve-operating means. In order to prevent excessive lateral movement of valve 15 in the opening 12, a guard 18' (Fig. 5) is provided, consisting preferably of a wire bent to form a circular portion at the center thereof, through which the stem 16 projects, and downwardly turned ends which may be driven into the material of the part 11. The circular portion formed in the wire 18' is considerably larger than the stem 16 of the valve, so that it does not form a bearing for the stem, but merely precludes lateral movement of the valve 15 in opening 12 to such extent that the operation of the valve will not be uniform and reliable. The opening 12 may be quickly formed by a suitable machine and its depth accurately gaged, and the valve 15 and annulus 17, constructed as above described, may be readily made of the exact thickness desired, so that provision for adjustment of the parts of the valve is rendered unnecessary. The valve 15 in the position in which it is shown in Fig. 2 permits air to be drawn from the pneumatic through the passage 13, opening 12 and passage 10 into the suction-chamber 1. When the valve is raised, it coacts with the flange on the inner edge of the annulus 17 to close this passage and to open a path for the air through passage 14, opening 12 and passage 13 to the pneumatic.

The valve 15 is operated by a puff of ordinary construction located upon the other part 18 of the central wall 2. This part 18 has an opening 19 therethrough, to which the puff 20 is connected, this puff having a strip 21 of stiffer material secured thereto in position to coact with the end of stem 16. The valve for controlling the pneumatic on the outer face of the part 18 is located within the part 18 in an opening 22 (Fig. 1) formed therein. This valve is operated by a puff 23 located on the part 11 of the wall 2 and supplied with air through a passage 24 leading through the part 17.

Means are provided for connecting the puffs 20 and 23 with openings on the tracker-board. In the drawings, I have shown devices for this purpose which are also used for supporting the double pneumatic upon the suction-chest 1. These consist of hollow screws 25 extending through openings in the walls of the suction-chest, their ends entering threaded openings in the parts 11 and 18 of the central wall 2 and communicating with the passages 24 and 19 respectively. To the outer ends of these screws, flexible pipes 26 and 27 are connected, these pipes leading to openings on the tracker-board in the usual manner.

The puffs 20 and 23 are normally collapsed,

due to the fact that a very small opening is formed in the tubular members 25 within the suction-chamber 1. When puff 20 is collapsed, the valve 15 is drawn to the upper position by the suction thereon and atmospheric pressure under the valve 15 and the pneumatic on the outer face of wall 11 is therefore connected with the atmosphere through passages 13, 12 and 14, and is disconnected from the suction-box by the coaction of valve 15 with annulus 17. When the music-roll, moving over the tracker-board, permits air to enter pipe 27, the puff 20 is expanded and moves the valve 15 downwardly until its lower face bears on the bottom of the opening 12 and its upper face is separated from the flange on the annulus 17. The connection of the pneumatic to the atmosphere is thus closed and the air in the pneumatic is quickly withdrawn therefrom through passages 13, 12 and 10 to the suction-box. This results in collapsing the pneumatic and operating the key of the instrument, as will be well understood.

It will be seen that in this manner a very compact arrangement of the parts is obtained, the two pneumatics being very thin, so that a single tier of them only is required to operate an upright piano. Greater compactness and protection of the delicate parts is obtained by placing the valves and their activating devices within the central wall of the double pneumatic. Furthermore, the construction is such that the pneumatics may be manufactured at very small cost, particularly as no delicate adjustment of any of the parts is required.

Having now described my invention, what I claim as new therein and desire to secure by Letters Patent is as follows:—

1. In a keyboard musical instrument, a pair of pneumatics having a common wall, two movable walls located one on either side of said common wall, and valve mechanism controlling the air supply of said pneumatics located within said common wall, keys, and connections between said movable walls and independent keys of the instrument, substantially as set forth.

2. In a keyboard musical instrument, a pair of pneumatics having a common wall, two movable walls located one on either side of said common wall, two valves each controlling the passage of air to and from one of said pneumatics, and an operating device for each of said valves, said valves and operating devices being located within said common wall, keys, and connections between said movable walls and independent keys of the instrument, substantially as set forth.

3. In a keyboard musical instrument, a pair of pneumatics having a common wall formed in two parts secured together, two movable walls located one on either side of said common wall, a valve located in each of

5 said parts of the central wall controlling the passage of air to and from one of said pneumatics, and a pneumatic device on each of said parts for operating the valve on the other part, keys, and connections between said movable walls and independent keys of the instrument, substantially as set forth.

10 4. In a keyboard musical instrument, the combination of a suction-chamber, a pair of pneumatics having a common wall and two movable walls one on either side of said common wall, two valves located within the common wall, passages formed in said common wall leading from each of said valves to the suction-chamber, the atmosphere and one of said pneumatics, keys, and connections between said movable walls and independent keys of the instrument, substantially as set forth.

15 5. In a keyboard musical instrument, the combination of a suction-chamber, a pair of pneumatics having a common wall formed of two parts secured together and two movable walls one on either side of said common wall, two valves located one in each of said parts of the common wall, a passage leading from the suction-chamber to said valves, passages formed in each of said parts leading from the valve therein to the pneumatic adjacent thereto and to the atmosphere, a pneumatic valve-actuating device located in each of said

20 parts, passages for carrying air to said devices, keys, and connections between said movable walls and independent keys of the instrument, substantially as set forth.

25 6. In a keyboard musical instrument, a support, a pneumatic, a pneumatically-actuated valve for said pneumatic, a hollow screw for securing the pneumatic to said support, a connection to one end of said screw for carrying air thereto, and a connection between the other end of said screw and the actuating devices of said valve, substantially as set forth.

30 7. In a keyboard musical instrument, a pair of pneumatics having a common wall and two movable walls one on either side of said common wall, an opening in said central wall, a metallic annulus partially closing said opening, a valve movable between the bottom of said opening and said annulus, a guide for said valve, passages through said common wall leading one to one of said pneumatics and one to atmosphere, keys, and connections between said movable walls and independent keys of the instrument, substantially as set forth.

35 This specification signed and witnessed this 29th day of October, 1907.
